UNITED STATES PATENT OFFICE.

PETER E. McDONALD, OF DETROIT, MICHIGAN, ASSIGNOR OF ONE-THIRD
TO S. O. BROOKS, OF SAME PLACE.

TICKET-HOLDER.

SPECIFICATION forming part of Letters Patent No. 388,895, dated September 4, 1882.

Application filed November 8, 1887. Serial No. 254,634. (No model.)

To all whom it may concern:

Be it known that I, PETER E. McDONALD, a citizen of the United States, residing at Detroit, county of Wayne, State of Michigan, 5 have invented a certain new and useful Improvement in Ticket-Holders; and I declare the following to be a full, clear, and exact description of the same, such as will enable others skilled in the art to which it appertains to 10 make and use the same, reference being had to the accompanying drawings, which form a part of this specification.

My invention relates to certain new and useful improvements in ticket-holders, and has 15 for its object more particularly the construction of a holder adapted to contain a continuous mileage-ticket, and to admit of the same being drawn therefrom and severed in a convenient and reliable manner.

20 My invention therefore consists of the combinations of devices and appliances hereinafter specified, and more particularly pointed out in the claims.

25 In the accompanying drawings, which form a part of this application for Letters Patent, Figure 1 is a view in perspective of a device embodying my invention, showing the cover raised to disclose the interior. Fig. 2 is a view in perspective with the cover in place inclosing the ticket. Fig. 3 is a longitudinal section, and Fig. 4 a vertical cross-section of the same.

I carry out my invention as follows:

30 A represents a ticket-holder, consisting of 35 covers A' and A'', the portion A' constructed with a pocket, A', to receive the ticket, the marginal edges of the portion A' being raised to inclose the edges and ends of the ticket, as shown at a, a', a'', and a''. The cover A'' is so constructed and so engaged with the corresponding portion, A', as to rest upon the said raised marginal edges and form a neat union thereupon to completely inclose the ticket when the two covers are in a closed position.

45 B is the ticket, consisting of a continuous strip folded at alternate ends and divided into a desired number of mileage-coupons, said ticket engaged in said pocket in any suitable manner to permit its being pulled out when 50 the coupons are to be detached. For this pur-

pose the rear end of the pocket may be provided with a retaining-sheet, C, of any suitable fabric, which may be secured or pasted upon the raised edges of the cover A'. This will hold the layers of the ticket in place even 55 when the covers are opened, and effectually prevent any disarrangement of the ticket, and so facilitate its operation.

The free end of the cover A'' is provided toward its extremity, but a little to the rear 60 thereof, with an elongated transverse orifice, a', of sufficient dimensions to permit the free movement of the ticket B through the same. Upon the extremity of said cover a', I also engage a suitable bar or loop, D, left free in relation to the transverse edge of said cover, so as to permit the end of the ticket being passed under the same and between it and the cover, as shown in Fig. 2, permitting the ticket being drawn out under said bar to release the 70 desired number of coupons. By locating the orifice a' a little to the rear of the said bar D a space, a'', of the cover will be left, against which the thumb may be pressed in the operation of moving out the ticket for the detachment of the coupons, affording thus particular facility in the operation of the ticket in its outward movement, as it may all be done with one hand, in which the ticket-holder is grasped.

75 The two covers of the holder may be secured in a closed position, if desired, in any suitable manner—as by a metallic clasp, E, which may be pivoted, as at e, so as to swing clear of the edges of the covers when it is desired to open the same.

80 The cover a'' may also be provided with a mileage scale, F, if desired, to facilitate taking up the fare, as the ticket may be conveniently turned backward over the band D, and so run out of its holder along the scale to indicate the 90 proper point at which the coupons should be detached for any given distance traveled. I would have it understood that this scale may or may not be marked upon the said cover, as may be preferred. As thus engaged in the 95 holder, the continuous folded ticket is free to be moved forward out of the holder, every facility being afforded for so doing and for detaching the coupons, while at the same time the folded layers of the ticket keep their place 100

and are not liable to bunch up; but each layer moves forward as required without disarranging the corresponding layers underneath.

The raised edge a^3 may be broadened, so as 5 to abut against the edges of the folded ticket at or near the slot a^1 . This will prevent the layers from being pulled forward in the pocket out of place.

I have described the ticket as passed under 10 the band; but, while this may be preferred, I do not limit myself thereto, as it is obvious that it is not essential to do this in order to sever the coupons, since the ticket may pass over said band, and I would have it understood that I 15 contemplate such a modification as coming within the scope of my invention. While I deem the employment of this band or loop to be desirable, it might, however, be wholly dispensed with, as the device will be very satisfactorily operative 20 without it. So, also, I have shown and described a metallic clasp to hold the covers together; but any suitable fastening may be substituted therefor, if preferred.

What I claim is--

25 1. A railway-ticket holder constructed with a ticket-discharge orifice in one of its faces intermediate of its ends, substantially as and for the purpose described.

2. A railway-ticket holder provided with 30 folding covers, one of said covers constructed with an elongated ticket discharge orifice intermediate of its ends, substantially as and for the purpose described.

3. A railway-ticket holder closed at its ends 35 and provided with an elongated orifice on one of its faces to permit the outward movement of the ticket through said orifice, substantially as described.

4. A railway-ticket holder constructed with 40 an elongated ticket-discharge orifice in one of its faces, and having in combination therewith a bar located upon the edge of said holder

forward of said orifice, substantially as described.

5. A railway-ticket holder provided with 45 an elongated orifice, having in combination therewith a bar upon its outer edge, said bar located at a little distance from said orifice, a portion of the holder being left between the orifice and bar, substantially as and for the 50 purpose described.

6. A railway-ticket holder provided with an elongated orifice, having in combination therewith a bar, said bar freed from the transverse edge of the holder to permit the passage of the 55 ticket between it and the holder, substantially as described.

7. A railway-ticket holder provided with folding covers, one of said covers provided with an elongated transverse orifice located 60 intermediate of the ends of the cover, and in combination therewith a fastening device to hold said covers together, substantially as described.

8. A railroad ticket holder, the said holder 65 constructed to form a pocket for the ticket and provided with an elongated orifice in one of its faces intermediate of its ends, through which the ticket may be moved outward, substantially as set forth. 70

9. A railway-ticket holder provided with folding covers, one of said covers constructed with raised margins to form a pocket to receive a ticket, and a ticket-retaining strip, C, substantially as described. 75

10. A railway-ticket holder provided with a mileage scale, substantially as described.

In testimony whereof I sign this specification in the presence of two witnesses.

PETER E. McDONALD.
